The ornamental design for a low profile transpyloric jejunostomy catheter, as shown and described.

DESCRIPTION

FIG. 1 is a top perspective view of the low profile transpyloric jejunostomy catheter according to the present invention.

FIG. 2 is a side view of the low profile transpyloric jejunostomy catheter illustrated in FIG. 1.

FIG. 3 is a bottom view of the low profile transpyloric jejunostomy catheter illustrated in FIG. 1.

FIG. 4 is an additional side view of the low profile transpyloric jejunostomy catheter illustrated in FIG. 1. The view illustrated is on a side that is opposite FIG. 2.

FIG. 5 is an additional side view of the low profile transpyloric jejunostomy catheter as illustrated in FIG. 1; and,

FIG. 6 is an additional side view of the low profile transpyloric jejunostomy catheter illustrated in FIG. 1. The view illustrated is on a side that is opposite FIG. 5.
